WATCH BRACELET OR SIMILAR ARTICLE

Kurt Speck, 540 Lawn Ave., Palisades Park, N.J.

Filed Jan. 9, 1963, Ser. No. 73,107

Term of patent 7 years

(Cl. D45—4)

The dominant features of my design reside in the portions shown in full lines.

I claim:

The ornamental design for a watch bracelet or similar article, substantially as shown and described.
